UNITED STATES PATENT OFFICE

171,621

ELECTRIC STEAM IRON

William J. Russell, New Britain, Conn., assignor
to Landers, Frary & Clark, New Britain, Conn.,
a corporation of Connecticut

Application September 8, 1953, Serial No. 26,723

Term of patent 7 years

(Cl. D49—6)

To all whom it may concern:

Be it known that I, William J. Russell, a citizen of the United States, residing at New Britain, in the county of Hartford, State of Connecticut, have invented a new, original, and ornamental Design for an Electric Steam Iron, of which the following is a specification, reference being had to the accompanying drawings forming a part hereof.

In the drawings:

Figure 1 is a perspective view of an electric steam iron embodying my new design;

Figure 2 is a side elevational view thereof;

Figure 3 is a front elevational view thereof;

Figure 4 is a rear elevational view thereof; and
Figure 5 is a bottom plan view thereof.

I claim:
The ornamental design for an electric steam iron, substantially as shown.

WILLIAM J. RUSSELL.
